UNITED STATES PATENT OFFICE.

JOHANNES F. SCHLEPER, OF AMSTERDAM, NETHERLANDS.

WIRE CLAMP.

Application filed February 20, 1920. Serial No. 360,233.

To all whom it may concern:

Be it known that I, JOHANNES FRANCISCUS SCHLEPER, a subject of the Queen of the Netherlands, residing at Amsterdam, the Netherlands, have invented certain new and useful Improvements in Wire Clamps, of which the following is a specification.

The invention relates to the provision of a cheap and reliable clamp for electric wires by which soldering of the wires may be completely dispensed with.

This and other features of my invention will be more readily understood by the following description, reference being had to the accompanying drawing in which:

Fig. 1 shows a longitudinal sectional view of a wire clamp constructed in accordance with the invention;

Fig. 2 is an elevation of a branch or distributing box with two wire clamps each for four wires, the cover plate being removed;

Fig. 3 is a sectional view, partly in elevation, and

Fig. 4 is a sectional view along the line 4—4 in Fig. 3, of a second embodiment of the invention;

Fig. 5 illustrates a sectional view of a third embodiment.

In Fig. 1 the bare ends of the cut cables 2 to be connected are passed lengthwise into a metal tubular member 1. The wall of the tubular member 1 is provided with some axially extending slots 4 opening into its top face 3, and the bare wire ends are bent over through said slots through nearly 180° in such a manner that they are received in grooves 5 cut in the wall of the member 1 with gradually decreasing depth. It is obvious that the bare wire ends are thus disposed along a conical surface. A rigid metal clamping ring 6 with a tapering inner surface is passed over the tubular member 1. The interior diameter of said ring 6 is such that the interior surface of the ring is held in contact with the bent-over wire ends. A nut 7, engaging with exterior screw thread on the member 1, serves for tightening the ring 6 whereby a close contact is produced between the bent-over end portions of the wires 2 at one side, and ring 6 and member 1 at the other side, whereby the desired electrical connection is ensured. A lock nut 8 may be used for preventing the nut 7 from working loose.

A rubber cap 9 is passed over the nut 7

and 7, the ring 6 and the bottom portion of member 1, thus ensuring the required insulation.

It will be understood that the ring 6 may be integral with nut 7, in which case the lock nut 8 may be dispensed with.

Fig. 2 illustrates how the described wire clamp may be used for branching two cables 14 and 15 of a lighting main. This figure need not further be explained.

In many instances it is very convenient to replace the rigid ring 6 by a sleeve or a cap of thin sheet metal. If such a sleeve or cap is forced tightly on the bent over bare wire ends, it is deformed in such a manner that it ensures a perfect electrical contact with all wires, even when the latter have different thicknesses. This cannot always be realized with a rigid clamping ring.

A wire clamp comprising such a thin sheet metal cap is illustrated in Figs. 3 and 4. The bare ends of the cut cables 2 are again passed into a tubular member and bent over through about 180° through axial slots 4 opening in the top face 3. Passed over the tubular member 1 and the bent over wire ends 2 is a cap 10 of very thin sheet brass so formed that its bottom does not engage the top face of the member 1 when the cap is simply put in place. The said cap 10 is forcibly pressed on the bare wire ends by means of a screw 11 extending through a hole in the bottom of the cap and screwed into the tubular member 1 which for this purpose is provided with an internal thread. The head of the screw 11 brings to bear a certain amount of pressure on the cap 10 which thereby is firmly pressed against the wire ends. Fig. 4 shows how the said cap, which originally had a circular cross sectional shape, is deformed and snugly fits around all wire ends. A rubber cap 9 is passed over the wire clamp when all pieces are correctly fitted.

In the described embodiments the bent-over wire ends are protected against moisture by the rubber cap 9, but some moisture may enter through the bottom opening of the tubular member 1 and thus impair a perfect electrical contact. With a view to avoiding this the tubular member 1 may be closed by a bottom piece 12 (see Fig. 5) provided with conical holes 13 corresponding in number with the number of wires to be connected. If the bare wire ends are passed into said holes until the bottom piece

covering is firmly pressed against the walls of the holes, perfectly tight joints are obtained.

The wire clamp shown in Fig. 5 is provided with a porcelain cap 9^a screwed on the tubular member 1.

Having now particularly described and ascertained the nature of my said invention and in what manner the same is to be performed, I declare that what I claim is:

1. An electric wire connector comprising in combination a member upon which the ends of wires are bent; arms extending from said member having slots between them through which the wire ends pass, said arms having screw threads thereon; means for engaging and holding the wire ends in bent condition; and a screw threaded member engaging the screw threaded arms and adapted when adjusted to bear down and clamp the last named means in position to hold the wire ends.

2. An electric wire connector comprising in combination a member having an upstanding collar over which the ends of wires are bent; arms projecting from said collar and having spaces between them to receive the wire ends and hold the same spaced; means surrounding said arms and adapted to engage the bent ends of the wires and electrically connecting the same; and means engaging said arms and also engaging said means surrounding the arms for causing the latter to clamp the wires and ensuring good electrical connection.

3. An electric wire connector, comprising a member having an upstanding collar over which the ends of the wires are bent, arms projecting from said collar and having spaces between them to receive the wire ends and hold the same spaced, means surround-

ing said arms and adapted to engage the bent ends of the wires and electrically connecting the same, said means being deformable to fit wires of different diameters, and means engaging said arms and also engaging said means surrounding the arms for causing the latter to clamp the wires and insure good electrical connection.

4. An electric wire connector comprising in combination a hollow tubular member through which the wires pass and upon which the bent ends of wires are disposed; a metal member adapted to simultaneously engage the bent ends of all the wires to make electrical contact therewith, said metal member being yieldable so as to securely engage wires of a number of sizes at the same time; and means for clamping the last yieldable metal member in effective position.

5. An electric wire connector, comprising a hollow member through which the wires pass and upon which the bent ends of the wires are disposed, said member being closed at its bottom by a wall perforated for the passage of the wires, arms projecting from said hollow member and having spaces between them to receive the wire ends and hold the same spaced, means surrounding said arms and adapted to engage the bent ends of the wires and electrically connecting the same, and means engaging said arms and also engaging said means surrounding the arms for causing the latter to clamp the wires and insure good electrical connection.

In testimony whereof I affix my signature.
JOHANNES F. SCHLEPER.
